UNITED STATES PATENT OFFICE

EDWARD LAFAYETTE, OF PITTSBURG, KANSAS

MEANS FOR BREAKING ROCK AND OTHER HARD MINERALS

Application filed April 18, 1932. Serial No. 606,030.

My invention relates to improvements in means for breaking rock and other hard minerals, and it consists in the combinations, constructions, and arrangements herein described and claimed.

An object of my invention is to provide a means for breaking rock and other hard minerals.

Another object of my invention is to provide means whereby the mineral in a vein or lode may be loosened after a suitable hole has been drilled in the lode.

A further object is to provide a shear-like construction consisting of two pivoted members, the lower ends of which are adapted to be placed in a suitable hole in the mineral and the upper end of which is adapted to be spread apart by a jack or any other suitable means; the spreading apart of the upper portion breaks or loosens the mineral so that it may be readily removed from its lode or vein.

Other objects and advantages will appear in the following specification, and the novel features of the invention will be particularly pointed out in the appended claims.

My invention is illustrated in the accompanying drawing, forming part of this application, in which:

Figure 1 is a front elevational view of a device embodying my invention, in which the opening position is shown in dotted outline,

Figure 2 is a side elevational view of the same,

Figure 3 is a top plan view, and

Figure 4 is a section taken along the line 4-4 of Figure 2.

In carrying out my invention I make use of two elongated breaker bars, 1 and 2, respectively.

The upper end of each of these bars is provided with an outwardly offset arm portion 3. The arm portions 3 are oppositely positioned with respect to each other and are adapted for receiving the opposite ends of a hydraulic jack or other suitable mechanism whereby the arms may be spread apart from each other under pressure. The inner faces

4 of the arms 3 may be provided with a recessed portion 5 for receiving the opposite

end of the jack or other mechanism not

shown. The recessed portion 5 may be semi-circular in shape or any other form adapted to provide an adequate engagement or abutment means whereby the jack or other mechanism may be prevented from slipping out 55 of engagement with the arms as they are spread apart.

Each of the bars 1 and 2 are preferably provided with a detachably secured spring 6 for returning the breaker bars to their closed 60 position after the jack has been removed. The spring 6 may be operatively secured by any suitable hook means such as, for instance, the threaded bolt and hooked nut construction 7.

Below the arms 3 each of the breaker bars consists of an integral elongated downwardly extending shaft or rod portion 8 which may be either semi-circular or angular in cross-sectional area. Each of the arms 3 is 70 provided with a transversely extending bore 9 for operatively receiving a pivot pin or shaft 10. The outer portions of the bore 9 may be countersunk and is indicated at 11 in order that the outer portions of the pin 75 or rod may be aligned with the adjacent surface of the shaft portions 8.

From the foregoing description of the various parts of the device of my invention, its operation may be readily understood.

The body of rock or mineral to be broken is drilled with one or more holes of sufficient length and cross sectional area to receive the shaft portions 8 of the breaker when the breaker is in the closed position. The arm 85 portions 3 extend above the opening and may incline downwardly and inwardly as is indicated at 11', in order to prevent the breaker from falling into a hole of greater depth than the length of the shaft portions 8. A jack or 90 other mechanism is then placed between the arms 3 and the arms 3 are gradually forced apart, as is indicated in the dotted line position shown in Figure 1. The coal or mineral surrounding the shafts 8 is thereby split apart 95 or broken, thus accomplishing the purpose of my invention.

The provision of the shafts 8 of semi-circular form in cross section with plane contacting faces is of advantage in that as the shafts 100

are moved on the pivot 10 by the jack, the edges of the shafts enter the surrounding mineral while the curved surfaces exert component forces in substantially opposite directions and approximately at right angles to the plane of movement of said shafts, whereby a splitting action is obtained.

It is obvious that each of the breaker arms must be made of a strong rigid metal such as, for instance, steel.

By drilling a plurality of holes in a vein or body of rock or other mineral and using the breaker mechanism in each of these holes, the entire body may be split or broken apart without the use of any explosives which are in some conditions extremely dangerous to use.

My method of breaking up a mineral body or vein is safe, convenient, economical, and it has the advantage of eliminating the delays incidental to the use of explosives such as, for instance, the delay incurred by waiting for the smoke to dissipate, and the delays incurred in waiting when the fuse or other ignition means fails to explode the charge of explosive.

I claim:

1. A mineral breaker comprising a pair of shafts, each having a plane surface and a surface semi-circular in cross section meeting in a longitudinal edge, said shafts being pivoted together intermediate the ends thereof with said plane surfaces in contact, spaced angular arms extending from corresponding ends of said shafts for receiving mechanism for swinging said shafts on said pivot to force said longitudinal edge of each shaft into the walls of an opening in which said shafts have been inserted whereby said curved surfaces exert wedging actions in opposite directions and substantially normal to the plane of said plane surfaces.

2. A mineral breaker comprising a pair of shafts each having a plane surface and a wedging surface terminating in a longitudinal edge, said shafts being pivoted together intermediate the ends thereof with said plane surfaces in contact, each shaft having cooperating extending arms at one end for receiving means for moving said shafts pivotally for forcing said longitudinal edges into the walls of an opening in the material in which said shafts have been inserted for causing said wedging surfaces to exert component forces in opposite directions substantially normal to the plane of said plane surfaces to split said material.

EDWARD LAFAYETTE.
